UNITED STATES PATENT OFFICE.

LOUIS H. PERLMAN, OF NEW YORK, N. Y.

WHEEL.

1,374,104.

Specification of Letters Patent.

Patented Apr. 5, 1921.

Application filed August 16, 1917. Serial No. 186,522.

To all whom it may concern:

Be it known that I, LOUIS H. PERLMAN, a citizen of the United States, residing at New York, in the county of New York and 5 State of New York, have invented certain new and useful Improvements in Wheels; and I do hereby declare the following to be a full, clear, and exact description of the invention, such as will enable others skilled 10 in the art to which it appertains to make and use the same.

This invention relates to improvements in demountable rims for cushioned tire vehicle wheels, and more particularly to such as are 15 adapted for use in conjunction with locking means of the general type disclosed in my United States Letters Patent No. 1,052,270, dated February 4, 1913.

An object in view is to facilitate the application and removal of the rim lock receiving means in the rim.

With this and further objects in view as will in part hereinafter become apparent and in part be stated, the invention comprises certain novel constructions, combinations and arrangements of parts as subsequently specified and claimed.

In the accompanying drawing,—

Figure 1 is a sectional elevation of a 30 wheel structure embodying the features of the present invention.

Fig. 2 is a fragmentary plan view looking at the inside face of a demountable rim.

Fig. 3 is a detail cross section through a 35 demountable rim showing the aperture in which the lock-receiving bolt is positioned.

Fig. 4 is a perspective view of one of the lock-receiving bolts detached.

Fig. 5 is a section taken on the plane indicated by line 5—5 of Fig. 1.

Fig. 6 is a perspective view of a slight modification of one of the lock-receiving elements showing the same detached.

Fig. 7 is a cross section therethrough, 45 taken on the plane indicated by line 7—7 of Fig. 6.

Referring to the drawing by numerals, 1 indicates a demountable rim having at preferably substantially uniformly spaced intervals radial apertures 2 formed through the web of the rim between its flanges. The form of flanges of the rim is immaterial so far as the present invention is concerned, and may be of any appropriate type, such 55 as disclosed in either Figs. 1 or 3, wherein

the same reference numerals will apply since the structure is otherwise identical.

A bolt or bolt-like device is extended through and fitted in each aperture 2, each bolt-like device consisting of a threaded shank 3 formed with a preferably integral head 4 at one end, the shank being bored longitudinally from the opposite head 4 to form a conical recess 5. The recess 5 is tapered substantially to correspond to the 65 taper of the locking wedge adapted to be introduced into said recess, as hereinafter described.

In applying the bolt-like device to the rim, one is supplied for each aperture 2 and 70 the shank 3 in each instance is introduced from the outside face of the web of the rim, through the respective apertures 2, and at the inside face of said web a nut 7 is provided and screwed on the threaded portion 75 of the shank for clamping the bolt-like structure firmly in position in engagement with the rim. That portion of the shank 3 nearest the head 4 is preferably not threaded so as to fit the aperture 2 and retain the 80 bolt-like structure against lateral displacement for shifting in the aperture.

The parts being assembled as described, and as seen in Fig. 1, the rim 1 is applied onto a wheel, such as seen at 8 in Fig. 1, 85 until the inner edge of the rim strikes the supporting stop flange 9 of the fixed rim or felly band 10 of the wheel. Thereupon, the tapered tip or wedge 11 of the bolt 12 is projected into the recess 3. The parts are 90 proportioned for causing the tapered tip or wedge 11 to enter a little off-center with respect to the recess 3, so as to wedge the rim over against the flange 9, and in the course of forcing the rim over the inner 95 portion of shank 3 is subjected to lateral pressure or stress which tends to distort the same, causing the threads to more deeply enter into the thread grooves of the nut 7 and thus engage or bind the nut firmly so as 100 to insure it against accidental displacement from the shank while the parts are in operative relation.

Referring to the modification as shown in Figs. 6 and 7 of the drawing, it will be 105 noted that the shank portion of the bolt-like structure 3' is split longitudinally as indicated at 3'', so as to more readily facilitate the distortion and binding action of this element in the application of the wedge. 110

11 thereon, the recess 5' and the head portion 4' being the same as hereinbefore illustrated and described.

5 The bolt 12 is anchored in the wheel body in the usual manner and as that anchorage and the bolt itself are not subject to claim in this application further detail description seems unnecessary. These features are fully disclosed in my above referred to U. S. Letters Patent in which the same are claimed.

10 An aperture (not shown) is provided in the rim 1 for admitting the passage of the valve stem, and it is perfectly obvious that so far as the present invention is concerned, 15 the rim may be of the old style clincher type, the Q. D. (that is, quick detachable) clincher or the straight-side type as preferred.

15 The several shanks 3 with their engaging wedges serve as drivers, transmitting rotary motion from the wheel body to the rim as well as retaining the rim against lateral separation from the wheel.

20 This application is a continuation of and substitute for my concurrently pending application Serial No. 105,691, filed June 24, 1916.

25 What is claimed is:—

1. The combination, with a wheel body 30 and a demountable rim, of a shank extending through the rim, means for retaining the shank against disengagement with the rim, the shank being formed with rim lock receiving means, and outwardly stressing and locking means on the wheel body engaging the shank.

2. The combination, with a wheel body 40 and a demountable rim, of a headed shank extending through the web of said rim, with a head on the exterior face of said web, means for retaining the shank against disengagement with the rim, the shank being formed with rim lock receiving means, and outwardly stressing and locking means on the wheel body engaging the shank.

3. The combination, with a wheel body 50 and a demountable rim, of a headed shank extending through the web of the rim, with a head on the exterior face of said web, means for retaining the shank against disengagement with the rim, the shank being formed with rim lock receiving means, and outwardly and laterally stressing means on the wheel body engaging the shank.

4. The combination, with a wheel body 55 and a demountable rim, of a headed shank extending through the web of the rim, with a head on the exterior face of said web, means for retaining the shank against disengagement with the rim, the shank being formed with rim lock receiving means, and laterally stressing means on the wheel body engaging the shank.

5. The combination, with a wheel body and a demountable rim, of a headed shank 65 extending through the web of the rim, with a head on the exterior face of said web, and outwardly and laterally stressing means on the wheel body engaging the shank.

6. The combination with a wheel body 70 and a demountable rim, of a headed shank extending through the web of said rim, with the head on the exterior face of said web, means for retaining the shank against disengagement with the rim, the shank being 75 formed with rim lock receiving means and outwardly and laterally stressing locking means on the wheel body for engaging the shank.

7. The combination with a demountable 80 rim, of an expansible shank engaging the web of the rim and having lock-receiving means adapted to effect expansion of the shank upon engagement of a rim lock.

8. The combination, with a demountable 85 rim, of a radially recessed laterally-expansible shank engaging the rim and adapted to receive rim locking means in its recess.

9. The combination, with a wheel body 90 and a demountable rim, of a shank extending through the web of the rim, and a nut engaging the shank for retaining the same in engagement with the rim, the shank being formed with rim lock receiving means, and outwardly and laterally stressing locking 95 means on the wheel body for engaging the shank.

10. The combination, with a demountable rim, of a radially recessed laterally expansible shank engaging the rim and adapted 100 to receive rim locking means in its recess, and a nut threaded onto the shank into engagement with the rim.

11. The combination, with a demountable rim, of a shank extending from the exterior 105 inwardly through the web of the rim, the shank being recessed longitudinally to receive wedge locking means for the rim in position to tighten the shank.

12. The combination, with a wheel body, 110 and a demountable rim, of a headed shank extending through the web of said rim with a head adjacent the exterior face of said rim, said shank being capable of distortion, means for retaining the shank against disengagement from the rim, and outwardly and laterally stressing means carried by the wheel body adapted to distort the aforesaid shank for the purposes set forth.

15 In testimony whereof I affix my signature 120 in presence of two witnesses.

LOUIS H. PERLMAN.
